ADJUSTABLE ARCH SUPPORT

Filed Feb. 11, 1939

UNITED STATES PATENT OFFICE

2,214,296

ADJUSTABLE ARCH SUPPORT

Joseph Early, New York, N. Y.

Application February 11, 1939, Serial No. 255,968

7 Claims. (Cl. 36—71)

Generically this invention relates to arch supports, but more particularly it is directed to supports of the adjustable type.

One of the principal objects of this invention is the provision of an adjustable arch support preferably adapted to be mounted within an inner sole and adjustable without removing the device therefrom, but which is adapted with equal facility to be positioned within a shoe without the inner sole.

An important object of this invention is the provision of an adjustable arch support having a base member and an arch supporting member movably connected therewith, and means intermediate the members for effecting relative adjustment of the arch supporting member with respect to said base member.

Another important object of this invention is the provision of an adjustable support having a base supporting element, and an arch supporting element slidably interconnected at its ends and one edge to said base element and means intermediate said elements for effecting adjustment of the arch supporting element with respect to the base element.

A still further object of this invention is the provision of an arch supporting device of this character comprising a base element, an arch supporting element, and an adjusting mechanism mounted intermediate said elements, finger grip means carried by said mechanism for effecting its adjustment and independently operable means carried by said arch supporting element for increasing the adjustable range of said mechanism.

With these and other objects in view, which will become apparent as the description proceeds, the invention resides in the construction, combination and arrangement of parts, hereinafter more fully described and claimed, and illustrated in the accompanying drawing, in which like characters of reference indicate like parts throughout the several figures, of which

Fig. 1 is a plan view showing the device as mounted with respect to an inner sole.

Fig. 2 is a side view of the device illustrated in Fig. 1.

Fig. 3 is a cross sectional view taken on the line 3—3 of Fig. 2 looking in the direction of the arrows.

Fig. 4 is a fragmentary sectional view taken at right angles to Fig. 3 and showing the adjusting plate in operative position.

Fig. 5 shows an enlarged detailed view of the adjusting screw with the hand grip means in extended position.

Fig. 6 is a section taken on the line 6—6 of Fig. 5.

There have been many attempts made to provide an adjustable arch support, but such supports with which I am familiar have proven deficient in many ways, some of which are: being difficult to effect adjustment and requiring extra tools, too complex and costly to manufacture, the adjustable mechanism not having sufficient range of adjustment or too bulky to be satisfactory, not presenting a substantially thin supporting device with the arch supporting member movably connected at its ends and one edge to the base member to permit satisfactory adjustment of said arch supporting member with respect to the base member; and it was to overcome such disadvantages by providing a substantially thin device having a base member, an arch supporting member movably connected thereto at its ends and one side, an adjusting means mounted intermediate said members at one edge so as to effect vertical adjustment of the arch supporting member centrally thereof, with longitudinal adjustment at its ends, and lateral adjustment at its connected edge with respect to said base member, said adjusting means comprising a compound adjusting screw means, hand grip means carried by said screws for effecting their actuation to relatively adjust the arch supporting member with respect to the base member, and a normally inactive adjusting plate operable to increase the normally adjustable range of said adjusting mechanism, that I designed the device forming the subject matter of this invention.

In the illustrated embodiment characterizing this invention there is shown an adjustable arch support device A and inner sole B, between the layers of which said device may be positioned and suitably secured.

Device A comprises a base plate 1 which may be stamped out of sheet metal or other suitable material, having one edge 2 curved inwardly in opposite directions to its ends 3 and 4 respectively, its opposite side being formed with an extension 5 offset with respect to the cross sectional median line 6 and, in the present instance, with straight edges 7 and 8 extending from its base to the opposite ends 3 and 4 of plate 1. Base plate 1 is formed on opposite side edges of extension 5 and ends 3 and 4 with lip portions 9 folded upon the base plate as at 9' and spaced with respect to the surface of said plate. A similarly shaped arch supporting plate member 10 is adapted to be mounted on the base member with its ends 11 and 12 and extension 13 slidably extending un-

der members 9; its curved edge spaced from edge 2 of said base plate 1 and tapering downwardly and outwardly therefrom in all directions to the opposite edges 7 and 8 and ends 3 and 4 of base plate 1, as will be apparent.

Members 1 and 10 spaced slightly from their edges as at 2 are formed with registering openings 15 and 16, respectively. The socket member 17 is formed with an extension 18 extending 10 through said opening 16 and riveted as at 19 to firmly secure said member 17 to the under surface of the arch supporting member 10, the walls of said opening 16 being beveled as at 20 so that the surface of said rivet head will be flush with 15 and form a continuation of the surface of member 10. The tubular screw member 21 externally and internally threaded as at 22 and 23, respectively, has one end reduced as at 22' adapted to extend in opening 15 flush with the outer surface 20 of base plate 1, the other end normally extending within and seating in socket 17. Threadedly mounted on said member 21 is a hexagonal or suitably shaped nut 24, in the present instance formed with an axial flange 15' adapted to extend through said opening 15. Flange 15' if desired may be dispensed with. Threadedly mounted within screw 21 is a telescoping adjusting screw member 25 similar to 21. In order that these screws may be relatively adjusted with respect to each other, screw 21 is formed with hinge lugs 26 in which the oppositely bent ends 27 of the semicircular finger grip member 28 are mounted, and an additional semicircular member 29 is hingedly connected to member 28 by hinge band 30 so that member 29 may be folded on member 28 and member 28 folded on the top edge surface of member 21 when not in use. A gripping mechanism similar to that described in connection with screw 21, except smaller, including member 31, lugs 32 and extensible member 33, is mounted on the end surface of adjusting screw 25. It will be noted that these finger grip mechanisms are adapted to foldably rest on the end surfaces of the screws so as not to interfere with the relative adjustable movements thereof.

Pivottally mounted at one side of said socket member 17 as at 34 is an auxiliary plate 35 normally resting in its inoperative position as shown 50 in Fig. 2, but movable into bridging relation with said socket member so as to form a seat for said screw elements, as shown in Fig. 4, thereby increasing the adjustable range of the compound screw unit C as will be hereinafter more fully explained.

The ends 3 and 4 of base plate 1 are formed with extension clip tabs 36 adapted to attach the support A to the inner sole B to maintain the device suitably positioned with respect thereto, 60 and similarly to the shoe if desired in the absence of the inner sole, or it may be positioned in the shoe without attaching, if desired.

In some instances it might be found desirable to form an opening through the shoe similar to 65 opening 37 formed in the inner sole to register with opening 15 so that adjustment of said supporting device may be effected without removing the shoe from the foot of the wearer.

While the operation of the device would seem 70 to be clear from the above description, it might be well to further state that initially the adjusting mechanism C is in complete telescoped or retracted position with plate 35 in its inoperative position (Fig. 2), and the initial adjustment is 75 effected by operation of nut 24 to actuate screw

21 in expanding direction in socket 17, or said screw 21 may be turned by the gripping members 28 and 29, and when the limit of adjustment of screw 21 is reached further adjustment is effected by actuation of screw 25 by the finger grip elements 31 and 33 which actuate said screw in extending direction within screw 21 to further adjust arch supporting plate 10 with respect to base plate 1 and when the limit of adjustment of said screws is reached, they may be returned to their initial positions and adjusting plate 35 moved into bridging position with respect to socket 17 whereby it is obvious that the range of adjustment of said arch supporting plate 10 is increased by the actuation of said screws as in the first instance.

From the above it will be apparent that I have designed an adjustable arch supporting device having a maximum range of adjustment with the adjusting mechanism normally representing a minimum of thickness, and comprising a base anchor plate, and an arch supporting plate shaped to conform to the natural arch of a person's foot, said members being movably connected at their ends and outer edge, and adjusting means mounted intermediate the members for effecting vertical adjustment of the arch supporting member at its highest point, longitudinal adjustment of its ends and lateral adjustment of its connected edge with respect to said base plate to give a maximum range of adjustment without necessitating an undue thickness of the supporting device, said device being simple in construction, easily adjustable without the necessity of extra tools, manufacurable at a reasonable cost, and efficient for the purposes intended.

Although in practice I have found that the form of my invention illustrated in the accompanying drawing and referred to in the above description as the preferred embodiment is the most efficient and practical, yet realizing that conditions concurrent with the adoption of my invention will necessarily vary, I desire to emphasize that various minor changes in details of construction, proportion and arrangement of parts, may be resorted to within the scope of the appended claims without departing from or sacrificing any of the principles of this invention.

Having thus described my invention, what I desire protected by Letters Patent is as set forth in the following claims:

1. An adjustable arch support including a base member and an arch supporting member movably connected at their ends and one edge, and an adjusting means intermediate the free edges of 55 said members to effect vertical adjustment of the free edge, longitudinal adjustment of the ends, and lateral adjustment of the connected edge of said arch supporting member with respect to the base member, said adjusting means including 60 telescoping screw elements, and finger grip means carried by each screw for effecting its independent operation.

2. An adjustable arch support including a base member and an arch supporting member movably 65 connected at their ends and one edge, an adjusting means intermediate said members for effecting relative adjustment of the arch supporting member with respect to the base member and a movable auxiliary plate means for increasing the 70 adjustable range of said adjusting means.

3. In combination with an inner sole, an adjustable arch support including a base member, an arch supporting member movably connected to said base member, an adjusting means inter- 75

mediate said members to effect relative adjustment of the arch support member with respect to the base member, said means including a screw means, means carried by said screw means for effecting operation thereof, and means movable into the path of said screw means to increase its adjustable range with respect to said arch supporting member.

4. An adjustable arch support including a base member, an arch supporting member movably connected to said base member at its ends and one edge, adjusting means intermediate said members to effect relative vertical adjustment of its free edge and longitudinal and lateral sliding adjustment of the ends and side edges, respectively, said arch supporting member on said base member, said adjusting means including an adjusting screw extending through said base member, a similar screw operable within said first mentioned screw, and operating means for effecting relative adjustment of said screws with respect to said arch supporting member and each other carried by each of said screws.

5. An adjustable arch support including a base member and an arch supporting member slidably connected at their ends and one edge, adjusting means intermediate the free edge of said members to effect relative adjustment of the arch supporting member with respect to the base member, screw engaging means carried by the arch supporting member, a compound adjusting screw mechanism seating on said base member coaxing with said screw engaging member, means movable into bridging relation with respect to the

screw engaging means to increase the adjustable range of the adjusting mechanism, and means for operating said mechanism.

6. An adjustable arch support including a base member and an arch supporting member movably connected at their ends and one edge, an adjusting means intermediate the free edges of said members to effect relative adjustment of the arch supporting member with respect to the base member, a screw engaging means connected to the arch supporting member, means movable into bridging relation with respect to said screw engaging means, a compound screw mechanism including an exteriorly mounted adjusting nut seating on said base member, and means for effecting the engagement in extending direction of said screw mechanism with said screw engaging means and said bridging means.

7. An adjustable arch support including a base member and arch supporting member movably connected at their ends and one edge, an adjusting means intermediate the free edges of said members to effect relative adjustment of the arch supporting member with respect to the base member, said adjusting means including a screw engaging means connected to the arch supporting member, telescoping screws including an exteriorly mounted nut seating on said base member, means carried by the respective screws for effecting their independent engagement with said screw engaging means, and means carried by said screw engaging means to increase the adjustable range of said adjusting mechanism.
